DESIGN FOR A KNITTING OR SEWING BOWL

William James Hamilton, Jr., Westfield, N. J.

Application February 17, 1940, Serial No. 90,339

Term of patent 7 years

To all whom it may concern:

Be it known that I, William James Hamilton, Jr., a citizen of the United States, residing at Westfield, in the county of Union and State of New Jersey, have invented a new, original, and ornamental Design for a Knitting or Sewing Bowl, of which the following is a specification, reference being had to the accompanying drawing, forming part thereof.

The figure is a plan view of a knitting or sewing bowl, showing my new design.

I claim:

The ornamental design for a knitting or sewing bowl, as shown.

WILLIAM JAMES HAMILTON, JR.
